12 Claims.

(Cl. 177—337)

This invention relates, generally to data transmission systems, and the invention has reference, more particularly, to a novel variable phase, two wire data transmission and control system.

Data transmission systems, i. e., electrical systems employed for transmitting various data such as angular data or data that are susceptible of indication on a suitable sheet, card or other member having relative movement with respect to a pointer or other designating means, as heretofore constructed, have generally required five or more wires extending between the transmitting or field station and the receiving or central station. The use of five wires not only greatly increases the installation and maintenance expense, but oftentimes five wires are not available for use in transmitting data, as during army maneuvers, when it is not practicable to string five wires from a transmitting station, such as an outpost, to a receiving or central station which may be several miles away. Also, such five-wire systems are particularly susceptible to all kinds of interference picked up in the transmitting lines. It therefore becomes highly desirable to provide a two-wire data transmission system, and one in which ordinary telephone wires may be used for transmitting the desired data, such wires being usually available in most locations.

The principal object of the present invention is to provide a novel, reliable and easily operated data transmission and control system, which system employs but two wires extending between the remotely located transmitting and receiving points.

Another object of the present invention lies in the provision of a novel data transmission and control system of the above character wherein a variable phase constant frequency signal is employed for transmitting the desired data from the transmitting point to the receiving point.

Still another object of the present invention is to provide a novel data transmission and control system of the above character having means for producing a synchronizing signal, preferably of low audio frequency, that is sent out from the receiver to the transmitter, at which latter means is provided for converting such signal to a higher and different frequency of variable phase position corresponding to the data transmitted, and then sending it back to the receiver, the latter being so constructed and arranged as to select the returning signal and detect its phase

position for use either in operating a follow-up indicator or, through use of a torque amplifier, to control a servo motor to effect the positional control of a controlled object, such as a search-light.

Another object of the present invention lies in the provision of a novel data transmission and control system of the above character that is entirely self-synchronous and continuously rotatable, the said system requiring but one frequency per channel, and being adapted to provide additional channels, as desired, over the same pair of wires by employing corresponding additional frequencies at the transmitting and receiving ends, these additional frequencies being separated from each other and from the frequency of the first channel by the use of suitable filters.

Still another object of the present invention is to provide a novel data transmission and control system of the above character that is easy to operate and is reliable in use, the said system having a small and compact transmitter that can be readily carried from place to place by one man.

Other objects and advantages will become apparent from the specification, taken in connection with the accompanying drawings wherein one embodiment of the invention is illustrated.

Fig. 1 is a schematic view showing of a single channel, two-wire data transmission system of this invention arranged for manual follow-up.

Fig. 2 is a wiring diagram of the system of Fig. 1.

Fig. 3 is a schematic view showing of a system similar to that of Fig. 1, but providing for automatic instead of manual follow-up.

Fig. 4 is a wiring diagram of the system of Fig. 3.

Fig. 5 is a schematic view showing a multiple channel, two-wire data transmission system.

Fig. 6 is a wiring diagram of the system of Fig. 5.

Similar characters of reference are employed in the above views to indicate corresponding parts.

Referring now to Fig. 1 of the drawings in connection with a brief description of a single channel system arranged for manual or hand follow-up, the reference numeral 1 designates the transmitter as a whole, whereas the reference numeral 2 designates the receiver. The receiver 2 comprises a constant speed drive motor 3 that is connected to drive a synchronous generator 4 that supplies a single phase voltage of low or timing frequency through leads 5 to a

line coupling or selecting network 6. From the network 6, the single phase voltage of timing frequency is supplied to a transmission line 7 of any desired length, and may be a commercial telephone line. At the transmitter end of this line a line balancing or selecting network 14 transfers the timing frequency to a frequency doubler 15 which converts the single phase voltage to one of double frequency and supplies the same to a network 16 that serves to break up the double frequency potential into three 120° components. This three phase different or double frequency output is fed to the three phase winding of a phase shifter device or transmitter "selsyn" 17 whose single phase winding is coupled to an amplifier 18. This amplifier makes up the losses incurred in frequency doubling and conversion to three phase and also serves to bring the outgoing variable phase different frequency signal to a voltage level suitable for transmission over the line 7. The amplifier output is coupled to the line through the selecting or line balancing network 14 which serves to separate the incoming low frequency voltage from the outgoing different or double frequency signal voltage. At the receiver, the selecting network 6 separates the double frequency signal voltage of variable phase from the timing frequency voltage supplied from generator 4 and couples the signal voltage to a detector 10. This detector is supplied with a second single phase voltage of twice timing frequency from the phase shifter device or receiver "selsyn" 20, similar to "selsyn" 17. "Selsyn" 20 is supplied with three phase voltage of double timing frequency by generator 4. The output of detector 19 is connected to a zero center meter 21.

In operation, rotation of the transmitter "selsyn" handwheel 22 causes the single phase, double frequency output or signal potential to be shifted in phase one degree for each degree the rotor of device 17 is turned. This signal potential, after passing through line 7 and terminal apparatus, is applied to detector 19, where it is compared as to phase with the output of receiver "selsyn" 20. If the transmitter and receiver "selsyns" are in correspondence, the meter 21 will show a zero reading indicating angular correspondence of the transmitter and receiver "selsyns", but on the other hand, if the meter pointer moves off center, the receiver handwheel 23 must be turned to the right or left, depending on the direction of the movement of the meter pointer 24, to bring the pointer back to zero, corresponding to synchronous positions of the transmitter and receiver "selsyns". These "selsyns" are shown provided with relatively movable data card and indicator means 25 and 26, whereby data received corresponds to that transmitted.

The wiring diagram of the system of Fig. 1 is shown in Fig. 2 and in this latter figure it will be noted that the multiple frequency generator 4 is shown in two parts, i. e., part 4' for generating the timing frequency voltage and 4'' for generating three phase voltage of double timing frequency. Thus, if 4' produces 300 cycle single phase current, for example, then 4'' will produce 600 cycle three phase current. The selecting network 6 consists of a frequency bridge tuned to the operating frequency of the timing single phase output of generator part 4'. This bridge has a reactance arm 8 and a resistance arm 9, the arm 8 acting as a pure resistance at the timing frequency and being exactly

balanced by resistance arm 9, whereby equal and opposite currents flow from lead 5 into the primary winding halves 10 and 11 of transformer 12, so that the current from generator part 4' does not induce voltage in the secondary of transformer 12 and hence does not apply voltage to the grids of detector tubes 13 and 13'. Hence, the output of generator part 4' is supplied to line 7 with substantially no loss and is conducted to the transmitter 1, at which the timing frequency voltage passes through the selecting or line balancing network 14, consisting of adjustable condenser 27 and resistance 28, in parallel, and through the primary of transformer 29, thereby applying a voltage to a full wave rectifier 30 of the frequency doubler 15.

This rectifier 30 is connected through a resistance 31 and condenser 32 to the primary of a transformer 33. The condenser 32 serves to remove the D. C. component produced by the rectifier 30, but permits both halves of the A. C. wave to pass through the primary of transformer 33. Thus, the rectifier serves, in effect, to cause all negative voltage peaks to become positive peaks and thus furnishes transformer 33 with two positive peaks for each positive peak supplied by the incoming timing frequency voltage. This double number of positive voltage peaks provides a different or double frequency voltage from the timing frequency, which voltage passes through the single to three phase network 16, where it is broken up into three 120° components and is then supplied to the three-phase rotor windings of the phase shifter device or transmitter "selsyn" 17. As the rotor of this device is turned by means of handwheel 22, each of its windings couples more or less closely in turn with the single phase winding 34 of this device or "selsyn," and since the mechanical distribution of the three-phase rotor windings is exact and the magnitudes and phase positions of the voltages supplied to these windings are in correct phase relation, the output signal voltage appearing across the winding 34 shifts in phase one degree for each degree of rotor movement.

Amplifier 18, consisting of triode 35 and the usual associated apparatus, raises the signal output voltage of "selsyn" 17 to a value suitable for transmission over the line 7, to which line this voltage is fed through transformer 36, leads 37 and selecting or line balancing network 14. Network 14 is adjusted so as to just balance the impedance of line 7, whereby current from leads 37 divides equally in the two halves of the primary of transformer 29, flowing in opposite directions therein so as not to apply the double frequency signal voltage to the rectifier 30.

At the receiver 2 this different or double frequency, variable phase signal voltage passes through the selecting network 6 and transformer 12 and is applied to the grids of detector tubes 13 and 13' of detector 19. The grids of these tubes are also supplied with a double frequency variable phase voltage from generator part 4'', this voltage passing from part 4'' to the three-phase windings of phase shifter or receiver "selsyn" 20, through single phase winding 38 thereof and transformer 39. When the voltage across the secondary of transformer 39 is 90° out of phase with the signal voltage across the secondary of transformer 12, the vector sums of these voltages reaching the grids of tubes 13, 13' are equal and therefore each of these tubes

(biased as detectors) draws the same amount of plate current through a respective half of resistor 40. Hence, there is no net voltage across the ends of resistor 40 and the meter 21 reads zero at the center of its scale.

When, however, the incoming double frequency, variable phase signal voltage is shifted in phase by reason of movement of handwheel 22 of transmitter "selsyn" 17, the 90° voltage relation of the voltages in transformers 39 and 12 is disturbed and the vector sums of these voltages reaching tubes 13 and 13' are no longer equal, and hence unequal plate currents flow in the two halves of resistor 40, producing a net unbalance voltage between the ends of this resistor and causing the pointer 24 of meter 21 to move to one side of the zero position. The receiving operator now turns the handwheel 41 of the receiver "selsyn" in the proper direction to cause angular movement of the rotor of this "selsyn" or phase shifter equal to that through which the rotor of the transmitter "selsyn" 17 has been turned by the transmitting operator, thereby realigning the phase position of the voltages across transformers 39 and 12, restoring the plate currents of tubes 13 and 13' to balance and bringing pointer 24 back to zero position, in which position the data indicated by pointer 26 on indicator card 25 of the receiver "selsyn" again corresponds to the data indicated by pointer 26 on indicator card 25 of the transmitter "selsyn".

In the form of the invention shown in Figs. 3 and 4, the equipment at the receiver is arranged to provide for automatic follow-up, so that as the transmitting operator rotates the dial 25 of his transmitter "selsyn" 17, the unbalanced voltages produced thereby in the detector-modulator 42 (see Fig. 3) of the receiver are utilized to operate, through suitable amplifier or motor control means 43, a pair of relays in circuit with a reversible motor 66 that may be used to operate a ponderable object, if desired. Motor 66 has a repeat-back connection to the rotor of receiver "selsyn" or phase shifter 20, whereby movement of the transmitter "selsyn" is automatically accompanied by a synchronous movement of the receiver "selsyn" 20, so that the data card reading of the receiver always corresponds to that of the transmitter.

Fig. 4 shows the wiring diagram of the system of Fig. 3. The transmitter in Fig. 4 is quite similar to that of Fig. 2, but is shown provided with a different type of selecting network 14'. This network consists of a band pass filter arranged to admit to the frequency doubler input transformer 29' the timing line frequency only and to sharply reject the double frequency variable phase output of amplifier 18' as well as any other extraneous voltages which may be present. The frequency doubler 15' is shown as employing two half wave rectifiers 30' for obtaining full wave rectification.

The selecting network 6' of the receiver 2 is similar to the network 14' of the transmitter and serves to prevent the timing generator frequency supplied by leads 5 through transformer 45 from reaching the detector input transformer 46, but readily passes the double frequency, variable phase signal potential from the transmitter "selsyn" to transformer 46 for application to the rectifier tubes 47 and 47' of the detector-modulator 42. The receiver detector circuit comprises the pair of half-wave rectifier tubes 47 and 47' supplied with a local comparison voltage

of double frequency from phase shifter or receiver "selsyn" 20, which voltage passes from winding 38 through transformer 48.

The phase relation of the signal and local comparison voltages necessary to obtain a condition of balance, is the same as that previously described in connection with Fig. 2, i. e., 90° displacement, and under this condition the voltages reaching rectifiers 47 and 47' are equal and the rectified voltage drops appearing across resistors 49 and 49' are equal and opposite, whereby the outer terminals of resistors 53 and 53' in the cathode-grid circuits of modulator tubes 50 and 50' are at the same potential. Tubes 50 and 50' are supplied with a low frequency voltage, such as a 60 cycle voltage, by way of leads 51 and transformer 52. As the incoming signal potential is shifted in phase, resulting in the unbalancing of the outputs of rectifiers 47 and 47', the gains of the modulator tubes 50 and 50' are similarly unbalanced and the 60-cycle voltage from transformer 52 is amplified more readily by one of these tubes than by the other and a net 60-cycle voltage reaches the transformer 54 in the output circuits of these tubes.

Transformer 54 passes this net 60-cycle voltage to the grids of relay operating tubes 55 and 55' of the motor control means 43 in 180° out of phase relation. These tubes are supplied with an A. C. plate voltage by leads 56 connected to 60-cycle supply leads 51 and hence the net voltage passing through transformer 54, resulting from the turning of transmitter handwheel 22, causes one of the tubes 55 or 55' to energize 35 the operating winding of one of the relays 57 or 57', whereby the contacts of such relay are caused to open, resulting in the rotation of the armature of motor 66. Motor 66 rotates in the proper direction to move the data card 25 of the receiver "selsyn" into synchronism with the corresponding card of the transmitter "selsyn" and where a ponderable controlled object 58 is driven from motor 66, such object is moved into synchronism with the transmitter "selsyn," the repeat-back 40 connection between motor 66 and the rotor of the repeater "selsyn" serving to re-establish the 90° phase relationship of the signal and local comparison voltages, thereby deenergizing the 45 energized relay 57 or 57' and stopping the motor 66 with the receiver indicating means 25, 26 in 50 correspondence with the corresponding transmitting means 25, 26.

The operation of motor 66 will be apparent when it is noted that the motor field winding 59 is permanently connected across the supply leads 60 and that the positive lead 60 feeds two equal resistances 61 and 61' that are adapted to be connected through normally closed relays 57 and 57', respectively, to the negative supply lead 60, the ends of each of the resistances 61 and 61' being connected to opposite brushes of the armature of motor 66. Opening of either one or the other of the relays 57 or 57' causes a large unbalance in the currents flowing in resistances 61 and 61' and the net voltage resulting therefrom is supplied to the armature of motor 66, causing the latter to rotate in a direction corresponding to the direction of the voltage unbalance.

When the receiver phase shifter or receiver "selsyn" 20 reaches a position of synchronism with the transmitter "selsyn," resulting in the deenergization of the energized relay 57 or 57', as the case may be, such relay closes so that the armature of motor 66 is short circuited through relays 57 and 57' in a full strength field

resulting in very strong dynamic braking and the immediate stoppage of the motor. In order to further insure against over-shooting and hunting of motor 66 about the position of synchronous alignment, resistors 63 and 63' are shown respectively connected to opposite brushes of motor 66 and are also connected to resistors 64 and 64' that are interposed between the two halves of the secondary winding of transformer 54. Changes in speed of the motor 66 corresponding to acceleration and deceleration of this motor produce variations in the back E. M. F. of this motor, which variations are applied to the grids of tubes 55 and 55' by virtue of the potential drops in resistors 64 and 64', the connections being such that the voltage produced across the armature of motor 66 acts on tubes 55 and 55' in a direction to cut the plate current of the driving tube 55 or 55', as the case may be, to zero before the phase shifter or receiver "selsyn" 20 is fully restored to synchronism, whereby motor 66 is brought to rest in a dead beat manner and without over-shooting or hunting.

When it is desired to transmit two or more channels of data over the same pair of transmission leads simultaneously, the somewhat modified system of Figs. 5 and 6 may be used. This system employs the same principles employed in connection with the preceding figures except that an additional high frequency is generated and varied in phase for each new channel desired. This necessitates the use of somewhat more complicated selecting networks at the transmitter and receiver stations in order to properly separate the various frequencies.

Referring to Fig. 5, the receiving station is provided with a synchronous multiple frequency generator 67 arranged to generate a fundamental frequency and additional higher frequencies, i. e., one for each channel desired. For multiple channel operation, it is preferable to have these higher frequencies bear no harmonic relation to each other in order to avoid inter-channel interference due to unwanted higher harmonics from either the timing or channel frequencies. The timing frequency produced by generator 67 is fed to the transmission line through the selecting network 68. At the transmitting station a selecting network 69 comprising a band pass filter passes this line frequency to transmitters 70 and 71, marked on Fig. 5 as A and B. Each of these transmitters 70 and 71 is similar to the single channel transmitter described in connection with Figs. 1 to 4, but is suitably modified to produce an output frequency suitable for its individual channel of operation. These output frequencies are fed through leads 72 and 73, respectively, to selecting network 68 and returned through line 7 to selecting network 68 at the receiving station. Selecting network 68 comprises two band pass filters, one of which passes the frequency corresponding to the output of transmitter 70 to the receiver 75, in which it is compared with a similar frequency from a suitable receiver "selsyn" or phase shifter fed from synchronous generator 67. In a similar manner, the frequency corresponding to the output of transmitter 71 is fed through the other band pass filter of network 68 to receiver 71, where it is compared, as before, to a similar frequency supplied from generator 67. Additional channels may be added, if desired, by the addition of other filters and additional generating apparatus to supply the local station comparison voltages.

Referring now to Fig. 6, showing a wiring dia-

gram of the system of Fig. 5, a suitable timing frequency voltage, for example, a 330 cycle voltage supplied from generator 67 (not shown in Fig. 6), is fed through leads 78 and transformer 5 79 to line 7, this timing frequency voltage being prevented from reaching the receiving circuits by the action of the band pass filters 74 and 76 of the selecting network 68. At the transmitting end, this timing frequency voltage is selected by the filter 79' of the selecting network 69 and passed to the frequency doubler 80 and through condenser 81 to transformer 82, through single phase to three-phase network 83, phase shifter or transmitter "selsyn" 84, amplifier 85 and transformer 86 back over line 7 to the receiving station. At the receiving station this signal voltage of double timing frequency, such as 660 cycles, and variable phase is selected by filter 74 and passed through transformer 86 to detector tubes 87 and 87' and compared with a locally generated A. C. supply (such as a 660 cycle supply) by observation of meter 90 and operation of receiver "selsyn" or phase shifter 91 by turning handwheel 92. Receiving dial 25 is thus brought into synchronous alignment with transmitting dial 25.

The operation of the second data transmitting channel is similar, in that at the transmitting end the timing frequency voltage, such as 330 cycles, selected by filter 79' of network 69 and doubled by frequency doubler 80, passes through condenser 81 to transformer 93 having its primary winding connected to the terminal of the secondary winding of transformer 94. Hence, 30 the double frequency voltage output of doubler 80 has added in series with it in transformer 93 the voltage appearing across one-half of the secondary winding of transformer 94. Thus, when using a 330 cycle timing frequency, the voltage reaching the grid of tube 95 is composed of 660 cycles plus 330 cycles. Tube 95 is biased as a modulator and hence its output circuit provides voltages of frequencies consisting of the sum and difference of frequencies of the voltages of its grid circuits. Thus, in the above example, one of these components is 330 plus 660, or 990 cycles. This frequency is selected by filter 96 and passed through transformer 97, single phase to three-phase network 98, transmitter "selsyn" or phase shifter 99, amplifier 100 and transformer 101 to line 7. At the receiving station this signal frequency (i. e., for example 990 cycles) of the second or B channel is selected by filter 76 and passed through transformer 102 to detector tubes 104 and 104' and is compared with a locally generated similar frequency (990 cycles in the example chosen) by the previously described means involving the zero center meter 105 and receiver phase shifter or "selsyn" 106, whereby the receiver "selsyn" indicator 25, 26 is brought into synchronism with the transmitter "selsyn" indicator 25, 26.

Although the system of Figs. 5 and 6, for the sake of simplicity, is shown as providing for two-channel transmission, it is to be understood that additional channels may be added, as desired, through the use of additional transmitting and receiving apparatus including proper filters. Thus, in Fig. 5, additional leads are shown for leading to apparatus for another channel.

The novel data transmission system of this invention thus provides one or more channels of data transmission over a single pair of leads, and if these leads are telephone wires, the operation of the data transmitting system will not inter-

fere with voice transmission over the same wires so long as suitable filters are used in the telephone apparatus to exclude data transmission frequencies.

The positional control of ponderable objects, as disclosed in connection with Figs. 3 and 4, is equally applicable to the multi-channel system of Figs. 5 and 6.

In all forms of the invention, the transmitter apparatus is light and compact and can be readily carried from place to place by one man.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. A data transmission and control system comprising a transmitter, a receiver, a two-wire transmission line interconnecting said transmitter and receiver, means for supplying said line with an alternating potential of fundamental frequency, said transmitter having means for converting said alternating potential to one of different frequency and of continuously variable phase position corresponding to the data transmitted, means for supplying said different frequency, variable phase potential to said line for transmission to said receiver, said receiver having means for selecting said different-frequency variable-phase potential and for detecting its phase position, an indicator operated in accordance with said phase position, and means for so operating said indicator.

2. In a control system of the character described, a two-wire transmission line, means for supplying said line with an alternating potential of fundamental frequency, a transmitting station connected to said line and having means for converting said alternating potential to one of different frequency, a receiving station connected to said line remote from said transmitting station, controlling means including a variable phase transmitter at said transmitting station for utilizing said different frequency potential to deliver electric signal impulses of changing phase to said line in accordance with data to be transmitted to said receiving station, means at the latter station for detecting the phase position of said signal impulses, and controlled means at said receiving station adapted to be operated in accordance with the output of said detecting means in synchronism with said controlling means.

3. In a control system of the character described, a two-wire transmission line, a transmitting station connected to said line, a receiving station connected to said line remote from said transmitting station, means at said receiving station for supplying a fundamental frequency potential to said line, a selecting network at said receiving station for delivering said potential to said line, a selecting network at said transmitting station for receiving said potential, means at said transmitting station for changing said potential to one of different frequency and for shifting the phase thereof in accordance with data to be transmitted, said transmitter selecting network acting to deliver said variable phase different frequency potential to said line for transmission to said receiving station, and said receiver selecting network acting to select

said variable phase potential, and means for using said potential in operating a controlled member.

4. In a data transmission and control system, 5 a two-wire transmission line, a receiver, a power supply at said receiver connected for supplying a fundamental frequency potential to said line, a transmitter having means including a frequency changer for changing said potential to one of different frequency together with a transmitter phase shifter for varying the phase position of 10 said different frequency potential in accordance with variations in the data transmitted, said variable phase different frequency potential being delivered to said line for transmission to said receiver, said receiver having a receiver phase shifter energized from said power supply and cooperating means for detecting the phase position of said variable phase potential, and means 15 cooperable with said detecting means for visually indicating said variations in the data transmitted.

5. A system of the character described comprising a two-wire transmission line, a receiver 20 comprising a multiple frequency generator, a selecting network connected to said generator and said line and serving to direct a single phase fundamental frequency potential from said generator onto said line, a transmitter comprising a frequency doubler, a selecting network 25 for receiving said single phase potential and for delivering the same to said doubler to be doubled in frequency, a transmitter "selsyn" having three phase and single phase windings, a network for converting the double frequency 30 single phase potential to a three phase potential for supplying the three phase winding of said "selsyn," an amplifier connected to the single phase winding of said "selsyn" and to said line for delivering an amplified version of the variable 35 phase double frequency signal output of said "selsyn" to said line for transmission to said receiver, a receiver "selsyn" at said receiver supplied with double frequency three phase potential 40 from said generator, said receiver having a detector supplied with a double fundamental frequency comparison voltage from said receiver "selsyn," a meter controlled by said detector, said receiver selecting network serving to direct said 45 variable phase double frequency signal potential to said detector, whereby variations of the relative angular positions of said transmitter and receiver "selsyns" cause said detector to operate said meter from zero position.

55 6. In a positional control system of the character described, a two-wire transmission line, a transmitter comprising a transmitter "selsyn" for supplying a variable phase signal potential to said line, a receiver comprising a receiver "selsyn," a thermionic phase position detector 60 connected to said line for receiving said signal potential, and a meter controlled from said detector, said receiver "selsyn" being connected to said detector for supplying a comparison potential thereto, whereby relative movement of 65 said transmitter and receiver "selsyns" serves to effect operation of said meter to indicate such relative movement.

7. In a variable phase data transmission and 70 control system for multiple channel transmission, a two-wire transmission line, a transmitting station having a plurality of transmitters for delivering continuously variable phase signal potentials of differing frequencies to said line, the phase of the signal potential output of each of

said transmitters varying in accordance with the data transmitted, and a receiving station having a plurality of receivers including phase detecting means for selectively receiving said signal potentials from said two-wire line and for controlling data indicators in response thereto.

8. A data transmission system comprising a transmitter and remote receiver, a two-wire channel of communication therebetween, means for supplying a variable phase potential over said line from said transmitter to said receiver for transmitting intelligence and means for also supplying a fundamental frequency voltage over said line from said receiver to said transmitter for use in energizing said variable phase potential supplying means.

9. A data transmission and control system comprising a transmitter station and a remotely located receiver station, a two-wire transmission line extending between the stations, means at the receiver station for supplying the line with A. C. potential of a predetermined substantially fixed frequency, means at the transmitting station for superposing upon the line a potential of a frequency differing from the fundamental frequency and in any desired phase position, and means at the receiver station proportionally responsive to any shift of the superposed phase position.

10. A data transmission and control system comprising a transmitter and a remotely located receiver, said system comprising a two-conductor transmission line as the only conducting means interconnecting said transmitter and receiver, said transmitter having means for delivering a variable phase signal potential that is variable without limit and corresponding to the data transmitted to said line for transmission to said

receiver, and said receiver having means for selecting and detecting the phase position of said signal potential for use in visually indicating the data transmitted.

5 11. A data transmission and control system comprising a variable phase transmitter for producing electric signal impulses of changing phase variable without limit to correspond to changes in data transmitted, a variable phase 10 receiver for receiving said signal impulses, said receiver being responsive to the varying phase output of said transmitter and having means for visually indicating the data transmitted, and a two-conductor transmission system serving as the only conducting means interconnecting said transmitter and receiver and transmitting said signal impulses to the latter.

12. In a control system of the character described, a two-conductor transmission line, a 20 variable phase transmitter having a controlling member and arranged for delivering electric signal impulses of changing phase to said line, said signal impulses being variable without limit as to phase in accordance with the position of said controlling member, a variable phase receiver connected to said line for receiving said signal impulses, and a controlled member located at said receiver, said receiver having means for detecting the phase position of said signal impulses and for operating said controlled member in response thereto, whereby said controlled member is moved synchronously with said controlling member, said two-conductor transmission line constituting the only electrical connection between said transmitter and receiver.
